HENRY HUEBER, OF BUFFALO, NEW YORK, ASSIGNOR TO TRICO PRODUCTS CORPORATION, OF BUFFALO, NEW YORK

HORN

Application filed April 5, 1932. Serial No. 603,427.

My invention relates to a fluid pressure operable horn for giving a warning note or signal, the device being particularly adapted for such use on an automobile, boat or 5 like vehicle.

More particularly, my invention relates to such a device, of the type having an elongated trumpet passage connected to a sound box, the latter containing a fluid pressure 10 actuated valve for intermittently interrupting the passage of fluid through the sound box and trumpet passage, whereby sound waves are created and emitted from the trumpet passage. The valve, which is 15 caused to oscillate toward and away from its seat at high frequencies by the differential fluid pressures effective against its opposite faces, is, according to the present invention, supported by helical spring means, 20 the axis of which is coaxial with the axis of oscillation of the valve. This permits of a simplified arrangement of parts and allows the comparative free angular movement of the valve, whereby the latter may seat 25 properly.

These and other objects and advantages including those inherent in the formation and arrangement of the component parts of the device, will become apparent from the 30 following description of the typical embodiment of the invention illustrated in the accompanying drawing, wherein:

Fig. 1 is an elevation of a complete horn, including the trumpet, sound box and fluid 35 pressure conduit;

Fig. 2 is an enlarged vertical section through the sound box and a portion of the trumpet depicted in Fig. 1; and

Fig. 3 is a perspective view of a spring 40 supporting and centering part shown in section in Fig. 2.

As illustrated in the drawing, the horn comprises an elongated and tapered tubular member or trumpet 11, preferably flared or belled at its enlarged and open end 12. Connected to the reduced end of the trumpet is a hollow casing or sound box 13, comprising a forward section 14 and a rear section 15. The forward section may be screw 45 threaded to the trumpet and locked there-

with by a lock nut 16. The casing section 15 is secured to casing section 14 in any suitable manner, as by screws indicated at 17, a gasket 18 being interposed between the casing sections. Extending from the casing 13 55 is a nipple 19 connecting a conduit 21 which may extend to a suction reservoir, the intake of an internal combustion engine, or other suitable source of fluid under pressure different than atmospheric. 60

The casing 13 is provided on its interior with an annular valve seat 22, the latter being preferably, although not necessarily, concentric with the axes of the trumpet passage and the opening 23, at the forward 65 end of casing 13, which forms a continuation of the trumpet passage. The inner edge of the valve seat 22 is delineated by a well or recess 24, in the casing interior, terminating in an annular shoulder or abutment 25. 70 Against the latter, within the well 24 is disposed a spring supporting member comprising an annulus 26 with a rearwardly projecting tubular hub 27, and spaced radial projections 28 abutting the shoulder 25. 75 Telescoping over the hub 27 and abutting the annulus 26 is a coiled helical spring 29.

A fiber disc 31, constituting a valve normally closing against valve seat 22 of the casing, is secured between weighted hub parts 32 and 33 by a screw 34, the latter being coaxial of the hub parts and the fiber disc. Hub part 32 extends into spring 29 and has a peripheral flange 35 abutting the end of the spring. Hub part 33 has portion 36 80 entering a second helical spring 37 and a shoulder 38 abutting the end thereof. Spring 37 preferably is axially aligned with the hub parts, the disc, and spring 29, and its end opposite the latter parts is seated with a cup 39. 85 Secured to the latter, or integral therewith, is a threaded shank 41 extending through a screw threaded opening 42 in a portion of the rear wall of casing 13, the wall being reinforced by a boss 43 about the opening. 90

The shank 41 may be adjusted axially by rotation to compress the springs 29 and 37, and, as the latter are compressed, the disc 31 will be moved toward the seat 22. To 95 secure the shank in any position of longi- 100

tudinal adjustment that is desired, a lock nut 44 is threaded over the shank against the boss 43. A cap 45, fitted over the boss and encasing the lock nut and end of shank 41, serves to improve the appearance of the device and to protect the threads of the shank.

To adjust the device for operation, the shank 41 is rotated to so compress springs 29 and 37 that the disc 31 will exert a slight pressure upon seat 22. When this condition is attained the spring 37 will be compressed to a slightly greater degree than the spring 35, the pressure exerted by the disc upon the seat 22 being equal to the difference between the pressures exerted upon the opposite faces of the disc by the springs.

In operation when thus adjusted, air will be withdrawn from the casing interior between the disc and casing section 15, through the outlet port or opening in nipple 19 and the conduit 21, to the source of suction, thereby decreasing the fluid pressure effective against the rear face of the disc to be-
low atmospheric. Simultaneously, atmospheric pressure will be exerted against the outer face of the disc (at the left in Fig. 2), and, when the difference in fluid pressures overcomes the spring pressure urging the disc to its seat, the disc will unseat, or move to the right as the device is illustrated in Fig. 2. Thereupon fluid under approximately atmospheric pressure will be admitted through the inlet opening and port 23 into the chamber at the rear face of the disc, so equalizing the pressure against the rear face with the pressure effective against the forward face, that the spring means will move the valve toward its seat. Continued withdrawal of fluid through conduit 21 will again cause a reduction of fluid pressure on the rear face of the disc so that atmospheric pressure against the forward face of the disc will again unseat the latter and the operating cycle will be repeated. Because of the extreme mobility of air, the cycles will recur at high frequencies, causing the air column in the trumpet and sound box to be alternately rarified and compressed at similarly high frequencies, thus effecting the emission of sound waves from the trumpet.

It is preferred that the frequency of the sound waves and frequency of oscillation of the disc 31 be correlated with the natural period of oscillation of the air column within the trumpet passage so that maximum resonance and volume of sound may be obtained with minimum expenditure of energy, and this may be accomplished by varying the mass of the disc assembly by varying the sizes of the hubs 32 and 33 and/or by adjusting the compression of the springs.

It will be understood that the device may be easily assembled or disassembled, the as-

sembly operations consisting of placing together the member 28, spring 29, the disc valve assembly, and the spring 37; of engaging these parts with the forward casing section 14; and then of attaching to the forward casing section, the rear casing section 15, to which the cup 39 and shank 41 have been attached.

It will be further understood that the device herein described and illustrated is merely representative and illustrative of one preferred manner of embodying the inventive principles involved, and that other embodiments employing these principles may be made, within the purview of my invention.

What is claimed is:

1. In a fluid pressure operated horn, a hollow casing having a pair of fluid ports therein, an annular valve seat between said ports, said casing having a shouldered recess extending from said seat to one port, a spider having a tubular hub seated in the recess in abutment with the shoulder thereof, a cup having a threaded shank extending through a threaded opening in the casing, a fiber disc normally abutting the annular seat, said disc having annularly shouldered hub parts on the opposite face thereof; a coiled spring between the spider and disc, and a second coiled spring between the disc and the cup, said first spring being seated over the tubular hub of the spider and extending over one hub part in abutment with the annular shoulder thereof, and the second spring extending over the other hub part in abutment with the annular shoulder thereof and seating within said cup.

2. In a fluid pressure operated horn, a hollow casing having a pair of fluid ports therein and an annular valve seat between said ports, said casing having a recess extending from said seat to one port, a member having an opening therethrough and being seated in said recess, a valve normally abutting the annular seat, a spring seating part carried by the casing, a member having spring seating means, and the valve having spring seating means on each face thereof, and a pair of aligned springs, one spring being between the member and valve, and the other spring being between the valve and said spring seating part.

3. A fluid pressure operated horn comprising a chamber having an outlet port and an inlet port, a reciprocatory member normally seating to close one port and adapted to be reciprocated away and toward said one port when a fluid stream is caused to move through the chamber from one to the other of said ports, a pair of compressed spring members disposed substantially in the line of reciprocation of the member for supporting it, and means for adjusting the degree of compression of said spring members.

4. A fluid pressure operated horn comprising

ing a chamber having an inlet and an outlet port, a reciprocatory member adapted to close one port and adapted to be reciprocated to produce sound pulsations when a fluid stream is caused to move through the chamber from one to the other of said ports, a coiled spring compressed on each of the opposite faces of said member, said springs being disposed substantially along the line of reciprocation of the members for supporting the member, and said springs being so compressed that the member is normally held in a position closing said one port.

5. In a fluid pressure operated horn, a hollow casing having a pair of ports therein, an annular valve seat between said ports, a vibratory member normally abutting said seat and having spring seating portions on the opposite faces thereof, a coil spring in engagement with each of said seating portions, said seating portions being recessed and having annular walls for respectively receiving and preventing lateral displacement of the adjacent end convolutions of 20 said springs, said springs being in substantially alignment and normally supporting said vibratory member in substantially closing relationship to said valve seat, and means extending from the walls of the casing for 25 supporting said springs.

6. In a fluid pressure operated horn, a hollow casing having a pair of ports therein and an annular valve seat between the ports, the casing having a shouldered recess extending from said seat into one of said ports, a spider seated in the recess in abutment with the shoulder thereof, a valve normally seated against said valve seat, a compressed spring between the spider and valve, a second spring at the opposite side of the valve in alignment with the first spring, and means carried by the casing for supporting the second spring, said means being adjustable to vary the tensions of the springs and 45 to vary the pressure of the valve against the seat.

7. A fluid pressure operated horn comprising a chamber having an outlet port and an inlet port, a reciprocatory member normally disposed in substantially closing relationship to one port and adapted to be reciprocated away and toward said one port when a fluid stream is caused to move through the chamber from one to the other of said ports, and a pair of compressed spring members disposed substantially in the line of reciprocation of the member for normally supporting it.

HENRY HUEBER.
